UNITED STATES PATENT OFFICE.

ERNEST G. H. SCHENCK, OF ORANGE, NEW JERSEY.

DESIGN FOR A CUT STONE.

SPECIFICATION forming part of Design No. 35,938, dated June 10, 1902.

Application filed May 8, 1902. Serial No. 106,500. Term of patent 14 years.

To all whom it may concern:

Be it known that I, ERNEST G. H. SCHENCK, a subject of the King of Belgium, and a resident of Orange, New Jersey, have invented and produced a new and original Design for a Cut Stone, of which the following is a specification, reference being had to the accompanying drawings, forming part thereof, of which—

10 Figure 1 is a plan view showing a bottom cut in accordance with my design, and Fig. 2 an elevation.

The embodiment of my design shown in the drawings consists of a generally circular figure having thereon an eight-armed star-shaped figure, each of which arms is formed of a four-sided pointed figure *a* and two elongated triangular figures *a'*. Between the arms

are a series of four-sided pointed figures *c*, and surrounding the arms and the figures *c* are five-sided figures or facets *d*, extending to the outer circumference of the design, and also a series of small triangular figures or facets *e*. At the center of the design is a star-shaped figure of quadrangular-pointed facets *b*. A conventional front is shown in dotted lines in Fig. 2.

What I claim is—

The design for a cut stone, substantially as herein shown and described.

Signed at New York, N. Y., this 17th day of April, 1902.

ERNEST G. H. SCHENCK.
